UNITED STATES PATENT OFFICE.

HORATIO J. BREWER, OF NEW YORK, N. Y.

GALVANIC BATTERY.

SPECIFICATION forming part of Letters Patent No. 359,055, dated March 8, 1887.

Application filed May 20, 1885. Serial No. 166,151. (No model.)

To all whom it may concern:

Be it known that I, HORATIO J. BREWER, of the city, county, and State of New York, have invented a new and useful Improvement 5 in Galvanic Batteries, of which the following is a full, true, and exact description, reference being had to the accompanying drawings.

This invention relates to an improvement in galvanic batteries, and is especially, though 10 not exclusively, applicable to closed batteries, which can be moved from place to place without damage or danger of spilling the liquids contained therein.

The parts new in my invention will be particularly pointed out in the claims hereto annexed.

The battery itself will be readily understood from the accompanying drawings, in which similar letters refer to similar parts.

20 Figure 1 is a view, generally in vertical section, of my improved battery. Fig. 2 is a view of the stopper, and Fig. 3 is a view of the jar.

A represents the battery-jar, made of any suitable material, which preferably is made 25 with vertical corrugations, as will be readily seen from the drawings. The bottom of this jar is by preference elevated in the center, where it has likewise a depression, K, for the reception of the lower end of the zinc. The 30 upper end of the jar has a neck of a suitable size for the reception of the stopper D. The electro-negative element in this battery consists of a sack, preferably made of cloth, containing the electro-negative substance in a powdered condition or reduced to small lumps. 35 In the form shown a long narrow sack arranged in a spiral form within the jar is employed. The substance to be placed in the bag may be of various kinds; but I prefer the common 40 pound heretofore patented to Georges L. Leclanché, though ordinary broken carbon could be employed with less advantageous results. The connection is made with this electro-negative body by means of a solid piece of carbon adapted to pass upward through the stopper. 45

In order to insure certainty of contact with this carbon plug H, I fill my sack as follows: The section of the carbon is generally arrow-shaped, the larger part projecting downward 50 and into the upper end of the sack.

The sack itself is provided with an opening large enough for the narrow end of the

carbon H to slip through, and the upper end of the sack is then firmly tied by a string, M, or in some other suitable manner, around the 55 neck of the carbon plug H. Of course I do not limit myself to this method of attachment, though it is a convenient one. The sack having been slipped over the neck of the carbon plug H, the material is filled into it from the 60 other end. By this means the material is firmly compacted between the sack and the carbon, and it thus enables a firm and permanent contact to be maintained between the carbon plug H and the filling N of the sack B. When the 65 sack has been firmly filled, the lower end is closed in some suitable manner, and the upper end can then be attached firmly around the carbon plug H by the string M. The sack should then be coiled in a spiral, as shown in 70 Fig. 1, the layers pressing firmly upon each other, and it should be of such a length as that when the upper coil is forced down, the upper projecting end of the sack should extend a little above the position it is to occupy 75 when the battery is completed. It will be observed that as this sack has been filled when straight, and is subsequently coiled in the cell, the coiling will reduce the interior capacity of the sack, and thereby still further tend to compact the granulated material contained therein. The neck of the carbon plug H is then to be fitted through the hole F in the rubber cork D, and when this cork is pushed firmly into its ultimate position in the neck it forces 80 down the sack into its ultimate position, thus still further insuring a firm contact between the carbon and the broken material in the sack. The battery-jar A having been filled with a suitable exciting-liquid—such as sal-ammoniac—the zinc rod Z is then placed in position by passing it through the opening E of the cork D. The lower end of the zinc rod then rests in the hollow K, while the lower end of the carbon coil is separated from it by the 85 circular elevation around the zinc. The cork D is likewise provided with an opening, P, which may have an automatic valve at its upper end. This is well made by making an opening extending almost through the rubber 90 cork and leaving a slit in the film at its upper end, as shown at G, Fig. 2. This opening will allow the escape of gases in case any pressure exists in the cell, but will not allow

the escape of the liquid. The corrugations R serve the double purpose of permitting a more extended contact of the liquid with the sack, and also of permitting the upward escape of 5 any gases which otherwise might be locked between the coils of the sack and the surrounding cell.

The conducting-wires are attached in the usual way for the zinc; but in connecting with 10 the carbon I prefer the method shown, in which a screw, J, provided with a suitable head has been baked into the upper end of the carbon, and a nut is then screwed down upon this screw, forcing the connecting-wire against 15 the upper end of the carbon. A very sure contact between the wire and the carbon is thus made.

The jar A, preferably made of glass and provided with the corrugations R, as shown, is 20 slightly elliptical in general section; but this shape is non-essential, and a round corrugated jar could be employed, or even a round jar without corrugations, though I find the corrugations very advantageous.

25 What I claim as my invention, and desire to secure by Letters Patent, is—

1. A flexible electro-negative element for a galvanic battery, consisting of a porous sack filled with granulated electro-negative material, 30 combined with a carbon plug in electrical connection with one end only of the sack, and serving as a connector for the electro-negative material, substantially as described.

2. The combination of the spirally-coiled 35 sack B, containing electro-negative material, with the carbon-connector H, projecting through the open mouth of the sack and into the body of the granulated electro-negative material, and the stopper D, substantially as 40 described.

3. The combination of the cell A, provided with corrugations R, and the spirally-coiled sack B, containing the electro-negative material N, substantially as described.

45 4. The combination of the cell A, provided with an inwardly-projecting bottom containing a central depression, K, elevated above the lower edge of the said cell, a spirally-coiled sack, B, resting on the bottom adjacent to the 50 walls of the cell, and the zinc C, placed therein and resting in the depression K, whereby the zinc and electro-negative element are separated from each other at all points and prevented from moving laterally by the shape of 55 the jar, substantially as described.

5. The rubber stopper D, provided with openings F and E and with the automatic gas-valve G, formed of the upper part of the rubber of the stopper D, substantially as described.

60 6. The combination of the corrugated jar A, the spiral sack B, coiled therein, the zinc C, and the stopper D, provided with openings F and E for the passage of the zinc and carbon connections, substantially as described.

7. The combination of a battery-jar, having 65 a less diameter at its neck than in the body of the jar, with a long sack containing electro-negative material inserted through the neck and spirally coiled against the inner surface of the jar, substantially as described. 70

8. The combination of a long sack containing a powdered or granulated compound of carbon and peroxide of manganese, provided with a carbon-connector pressed against the granulated electro-negative material and forming an 75 electrical connection therewith, and a jar in which the said long sack is spirally coiled, substantially as described.

9. A flexible electro-negative element for batteries, consisting of a flexible porous coiled 80 sack filled with electro-negative material, combined with a plug formed of conductive and non-corrosive material and projecting into the mouth of the sack, substantially as described.

10. A flexible electro-negative element for batteries, consisting of a porous sack filled with granulated electro-negative material, combined with a plug connected to one end only of said sack and formed of conductive and non-corrosive material, and a receptacle provided with a non-conductive and non-corrosive stopper, through and above which the plug extends, substantially as described. 85

11. As an article of manufacture, a connector for the negative element of a battery, the said connector being formed of a short plug of conductive and non-corrosive material carrying at one end means for connecting a wire thereto, substantially as described. 90

12. As an article of manufacture, a connector for the negative element of a battery, the said connector consisting of a plug of carbon enlarged at one end and carrying a binding-post at the other end, substantially as described. 95

13. As an article of manufacture, a connector for the negative element of a battery, consisting of a plug of carbon enlarged and pointed at one end and at the other end carrying a binding-post, substantially as described. 100

14. A negative element for batteries, consisting of a porous sack filled with granulated electro-negative material, combined with a connector consisting of a plug of non-corrosive material having one end enlarged and inclosed by one end of said sack, substantially as described. 115

In testimony whereof I have signed my name to this specification in the presence of two subscribing witnesses. 120
